UNITED STATES PATENT OFFICE.

CHARLES S. CHAMPION, OF NEW YORK, N. Y., ASSIGNOR TO WYCKOFF, SEAMANS & BENEDICT, OF ILLION, NEW YORK, A CORPORATION OF NEW YORK.

TYPE-WRITING MACHINE.

SPECIFICATION forming part of Letters Patent No. 752,885, dated February 23, 1904.

Application filed October 10, 1903. Serial No. 176,529. (No model.)

To all whom it may concern:

Be it known that I, CHARLES S. CHAMPION, a citizen of the United States, and a resident of the borough of Brooklyn, city of New York, in the county of Kings and State of New York, have invented certain new and useful Improvements in Type-Writing Machines, of which the following is a specification.

My invention relates to type-writing machines, and more particularly to stop mechanism therefor.

In various characters of type-writing work such, for instance, as in taking testimony it is desirable at times to move the carriage beyond the point where it is normally arrested in order to write within the margin, so that the characters "Q 21," "XQ 32," or "RDQ 46," for example, may appear within the margin.

The object of my invention is to provide efficient means which may be readily actuated to accomplish this result and to enable an operator to move the carriage beyond the point where it is normally arrested without occasioning further delay than is necessary to re-

turn the carriage.

To the above and other ends, which will hereinafter appear, my invention consists in the various features of construction, arrangements of parts, and combinations of devices to be hereinafter more fully described, and particularly set forth in the appended claims.

In the drawings, wherein like reference characters indicate corresponding parts in the various views, Figure 1 is a plan view of a machine embodying my invention. Fig. 2 is an end elevation with parts broken away, showing the upper portion of a machine with my improvements applied thereto. Fig. 3 is an enlarged detail plan view of certain of the devices embodying my invention, the view illustrating the normal disposition of the parts except as to the locking-tooth. Fig. 4 is a like view of the same, showing the disposition of the parts when the carriage has traveled beyond the point where it is normally arrested. Fig. 5 is a detail perspective view of the devices shown in Figs. 3 and 4, and Fig. 6 is an enlarged detail perspective view of the locking devices to be hereinafter described.

I have illustrated my invention in its application to a No. 6 Remington type-writing machine, though it should be understood that the invention may be applied to various characters of writing-machines and that numerous changes may be made to facilitate such application.

The top plate 1 of the machine has upwardly-extending supports 2 and 3, the former supporting a traverse-rod 4 and the latter a traverse or guide rod 5. The platen-frame 6 is pivoted at 7 to links 8, which in turn are pivoted to a truck 9. The pivot-pins 7 extend beyond their bearings and coöperate with set-screws 10 and 11 to limit the shifting movement of the platen-frame. The frame 6 supports a platen 12 and carries at the forward portion thereof a traction-roller 13, that bears upon a shift-rail 14 and supports the platen-frame in place at the forward end thereof. Extending forwardly from the platen-frame is the usual hand-lever 15, which is pivoted at 16 to a forwardly-extending ear 17, which projects from the platen-frame at the right-hand end thereof, and this hand-lever controls the line-spacing mechanism and is effective to actuate the carriage-release mechanism (not shown) in the usual manner. The truck 9 carries rollers 18, that are supported upon the rod 4, and a rearwardly-extending arm 19 projects from the carriage, and its rear bifurcated end coöperates with a sliding sleeve 20, that surrounds the traverse or guide rod 5. Supported between the upright supports 3 is the usual rack-bar or stop-rod 21, which is graduated to correspond to the letter-space movements of the carriage in its travel from end to end of the machine. Extending rearwardly from the carriage is a margin-stop 22, which ordinarily coöperates with a suitable stop on the stop-rod to limit the carriage in its movement from left to right.

So much of the machine as has thus far been described constitutes portions of the No. 6 Remington machine.

The stop-rod 21 constitutes a support for a sliding sleeve 23, mounted thereon, and projecting forwardly from this sleeve or slide is

a margin-stop 24, which extends into the path of and with which coöperates the stop 22 on the carriage. The slide 23 has a locking device 25 pivoted thereto at 26, and said locking device is in the nature of a lever which has a spring 27 secured thereto, the free end of said spring bearing against a pin 28, that is carried by the slide. The free end of this lever-like locking device has an upwardly-extending pin 29 and a downwardly-projecting portion 30, from which a forwardly-extending tooth 31 projects. The parts 30 and 31 are received within a slot 32 in the slide 23, and from an inspection of Fig. 3 it will be understood that the forwardly-extending tooth 31 on the locking device is adapted to engage between the teeth 33 on the stop-rod and is normally maintained in such locking engagement by the spring 27. The slide 23 carries a forwardly-extending apertured ear 34, which receives a headed spindle 35, that is adapted to move freely through the aperture therein, and the right-hand threaded end of this spindle is received within a threaded opening in a lug 36 on a slide or stop 37. A coiled expansion-spring 38 surrounds the spindle and bears at one end against the part 36 and at its opposite end against the ear 34 on the slide 23, and the pressure of this spring is exerted to force the slides 23 and 37 away from each other. The slide 37 carries a spring-restored locking device 39, by means of which the slide is normally locked in engagement with the teeth 33 on the stop-rod, but may be adjusted along the stop-rod with the slide 23 when desired. Extending upwardly from the slide 37 is a lug 40, which is apertured for the reception of a slide 41, that is headed at one end, 42, and has a cam 43 at the opposite end thereof. This slide is held in its adjusted position on the part 40 by a set-screw 43, the stem of which is received within a threaded opening in the part 40 and bears at its inner end against a side edge of the slide 41.

A lever or finger-piece 44 is pivoted at 16 to the forwardly-extending ear 17 of the platen-frame and is maintained in its normal position by a spring 45. This lever has a rearwardly-projecting crank-finger 46, that coöperates with the forward end of a lever 47, which is secured at its rear end to a rock-shaft 48, received in bearings 49 on the truck and fixed against longitudinal movement in said bearings. The inner end of the rock-shaft 48 carries a rearwardly-extending crank-arm 50, that has a cam 51 on the rear end thereof. This cam is located just to the right of the carriage-stop 22 and in its travel with the carriage is normally above the pin 29 on the locking device.

In the ordinary operation of the machine the movement of the carriage from left to right will bring the margin-stop 22 on the carriage into engagement with its coöperat-

ing stop 24, and the slide 23 being at this time locked to the stop-rod will arrest the carriage at the point determined by the position of the stop 24. This position may be changed by releasing the locking members 29 and 39 and moving both slides so that the stop 24 will be locked in a position where it is desired to arrest the carriage. Should the operator desire to move the carriage beyond the point where it is normally arrested by the stop 24, it is merely necessary to depress the lever 44, which causes an elevation of the forward end of the lever 47, and this results in rocking the shaft 48 and depressing the cam 51 so that in the travel of the carriage from left to right this cam will be brought into contact with the pin 29 on the locking device and will automatically release it from engagement with the teeth 33 on the stop-rod, as represented in Fig. 3. At about the moment when the locking device is released from the stop-rod, thus releasing the slide 23, the carriage-stop 22 engages the coöperating stop 24 on the slide and moves the slide toward the right with the carriage and against the tension of the spring 38. The initial movement of the slide 23 with the carriage toward the right brings the pin 29 above the highest portion of the cam 43 and to the rear of the edge 52 on the slide 41, as illustrated in Fig. 4. The movement of the slide 23 with the carriage may continue until the slide 23 is arrested by the fixed slide 37, when a further movement of the carriage to the right cannot take place. The operator proceeds to write within the margin, and in the continued movement of the carriage from right to left the slide 23 will follow the movement of the carriage, being pressed in that direction by the spring 38, and the locking device 25 at this time being held out of engagement with the stop-rod by the controlling device 41. As soon, however, as the pin 29 passes the cam 43 the locking device is forced by its spring 27 to reëngage between the teeth of the stop-rod, and thus again automatically lock it in its initial position.

From the foregoing description it will be understood that an adjustment of the part 41 determines the extent of movement that the slide 23 may make from right to left before it is locked to the stop-rod and that when the part 41 is secured in its adjusted position the slide 23 will always be automatically restored to and be locked in the same initial position during the return movement of the carriage from its position beyond the point where it is normally arrested by the stops. This device therefore determines the distance that the carriage may travel beyond the point where it is normally arrested. Thus, for instance, if the cam 43 is adjusted so as to release the pin 29 when the slide 23 is five letter-space distances from the slide 37 then a movement of the carriage may take place for

five letter-space distances beyond the point where it is normally arrested. If, on the other hand, the cam 43 is adjusted so that it will release the pin 29 when the slide 23 is at 5 ten letter-space distances from the slide 37, then the slide 23 will be automatically locked at ten letter-space distances from the slide 27 and a movement of the carriage is afforded for ten letter-space distances beyond the point 10 where it is normally arrested by the stops.

From the foregoing description it will be understood that the stop 24 at all times remains in the path of the stop 22 and that neither of said stops is moved transversely 15 to the travel of the carriage in order to afford writing within the margin—in other words, the margin-stops never pass each other and are always in coöperative relation—but that, nevertheless, hand-operated means, such as the 20 lever 44, are provided to afford through the travel of the carriage a movement thereof beyond the point where it is normally arrested by bringing the cam 51 into contact with the locking device 25 and that the hand-controlled 25 cam 51 is rendered effective by a movement of the carriage from left to right to disengage the locking device 25 and to afford a receding movement or displacement of the stop 24 from its normal position and in the general 30 direction of the travel of the carriage, so that the operator may write within the margin. Furthermore, it will be seen that when the lever 44 is depressed the return movement of the carriage automatically brings about the 35 unlocking of the locked stop and automatically brings about the receding or shifting movement of the unlocked or shiftable stop and that the movement of the carriage from right to left affords an automatic return of 40 the unlocked stop and affords an automatic locking thereof in the initial or normal position, or the position from which it was moved.

The stop 24 may be regarded as an initial stop, since it is adapted to arrest the carriage 45 at the initial arresting-point during the normal operation of the machine, and the stop 37 may be regarded as a final stop, since it arrests the final movement of the carriage, or the movement thereof after the locking device 25 50 is released.

Various changes may be made without departing from the spirit of my invention.

What I claim as new, and desire to secure by Letters Patent, is—

55 1. In a type-writing machine, the combination of a carriage, a stop on the carriage, a coöperating stop on the frame of the machine, said stops normally coöperating to arrest the carriage at a predetermined point in the travel thereof, and means for affording a movement of the carriage beyond the said predetermined point in the travel thereof without removing said stops from coöperative relation.

60 2. In a type-writing machine, the combination of a carriage, a stop on the carriage, a co-

operating stop on the frame of the machine, said stops normally coöperating to arrest the carriage at a predetermined point in the travel thereof, and hand-controlled means which through the travel of the carriage affords a 70 movement thereof beyond said predetermined point in its travel.

3. In a type-writing machine, the combination of a carriage, a stop on the carriage, a coöperating stop on the frame of the machine, 75 said stops normally coöperating to arrest the carriage at a predetermined point in the travel thereof, one of said stops being adapted to be moved from its normal position when the stops are brought into contact, thus affording 80 a movement of the carriage beyond said predetermined point, and hand-controlled means that are rendered operable by the travel of the carriage for determining when said stop may be moved from its normal position. 85

4. In a margin-stop mechanism for type-writing machines, the combination of coöperating stops which normally arrest the carriage at a predetermined point in its travel, one of said stops being adapted to recede from its 90 normal position in the general direction of the travel of the carriage to afford a further movement thereof beyond the point where it is normally arrested, means for automatically returning the stop to its normal position, and 95 means for determining when said recedable stop may be moved from its normal position.

5. In a margin-stop mechanism for type-writing machines, the combination of a carriage, a stop on the carriage, a coöperating 100 stop on the frame of the machine, means for locking one of said stops in its normal position to arrest the carriage at a predetermined point in the travel thereof, and means for effecting an automatic unlocking of the said 105 locked stop to afford a travel of the carriage beyond the point where it is normally arrested by the stops.

6. In a margin-stop mechanism for type-writing machines, the combination of a carriage, a stop on the carriage, a coöperating 110 stop on the frame of the machine, means for locking one of said stops in its normal position to arrest the carriage at a predetermined point in the travel thereof, means for effecting an automatic unlocking of the said locked 115 stop to afford a travel of the carriage beyond the point where it is normally arrested by the stops, and means for automatically locking the unlocked stop when the carriage returns to the 120 point where it is normally arrested.

7. In a margin-stop mechanism for type-writing machines, the combination of a carriage, a stop on the carriage, a coöperating 125 stop on the frame of the machine, means for locking one of said stops in its normal position to arrest the carriage at a predetermined point in the travel thereof, and means for effecting an automatic unlocking of the said locked stop and affording a movement thereof 130

in the general direction of the travel of the carriage to afford a movement thereof beyond the point where it is normally arrested by the stops.

- 5 8. In a margin-stop mechanism for type-writing machines, the combination of a carriage, a stop on the carriage, a coöperating stop on the frame of the machine, means for locking one of said stops in its normal position to arrest the carriage at a predetermined point in the travel thereof, means for effecting an automatic unlocking of the said locked stop and affording a movement thereof in the general direction of the travel of the carriage to afford a movement of the carriage beyond the point where it is normally arrested by the stops, and means for automatically restoring the unlocked stop to its normal position and for locking it in such position after the carriage returns from the point beyond that where it is normally arrested.
- 10 9. In a margin-stop mechanism for type-writing machines, the combination of a carriage, a stop on the carriage, a coöperating stop on the frame of the machine, means for adjusting one of said stops in the direction of the travel of the carriage, means for locking one of said stops in its normal position to arrest the carriage at a predetermined point in the travel thereof, and means for effecting an automatic unlocking of the said locked stop to afford a travel of the carriage beyond the point where it is normally arrested by the stops and as determined by the adjustment of said adjustable stop.

- 15 10. In a margin-stop mechanism for type-writing machines, the combination of a carriage, a stop carried by the carriage, a stop carried by the frame of the machine, said stops coöperating to normally arrest the carriage at a predetermined point in the travel thereof, and means carried by the carriage for effecting an automatic movement of one of said stops on its support in the general direction of the travel of the carriage.

- 20 11. In a margin-stop mechanism for type-writing machines, the combination of a carriage, a stop carried by the carriage, a stop carried by the frame of the machine, said stops coöperating to normally arrest the carriage at a predetermined point in the travel thereof, means carried by the carriage for effecting an automatic movement of one of said stops on its support in the general direction of the travel of the carriage, and means for automatically restoring the said stop, which is movable on its support, to the normal position.

- 25 12. In a margin-stop mechanism for type-writing machines, the combination of a carriage, a stop carried by the carriage, a stop carried by the frame of the machine, said stops normally coöperating to arrest the carriage at a predetermined point in the travel thereof, means for locking one of said stops to its support, means for affording a movement of said

last-mentioned stop independently of its support, and a finger-piece carried by the carriage and controlling the release of said locking means, whereby when the locking means are released the unlocked stop may be automatically moved and the carriage may move beyond the point where it is normally arrested. 70

13. In a margin-stop mechanism for type-writing machines, the combination of a carriage, a stop carried by the carriage, a stop carried by the frame of the machine, said stops normally coöperating to arrest the carriage at a predetermined point in the travel thereof, means for locking one of said stops to its support, means for affording a movement of said last-mentioned stop independently of its support, a finger-piece carried by the carriage and controlling the release of said locking means, whereby when the locking means are released, the carriage may move beyond the point where it is normally arrested, means for automatically restoring said released stop to its normal position when the carriage moves back from the point beyond where it is normally arrested, and means for automatically locking said released stop when it is moved back to the normal position. 85

14. In a margin-stop mechanism for type-writing machines, the combination of a carriage, a stop on the carriage, a coöperating stop on the frame of the machine, means for locking the stop on the frame of the machine in position, and means carried by the carriage for releasing said locking means. 90

15. In a margin-stop mechanism for type-writing machines, the combination of a carriage, a stop on the carriage, a coöperating stop on the frame of the machine, means for locking the stop on the frame of the machine in its normal position, and means carried by the carriage for releasing said locking means and for moving the stop controlled by said locking means from its normal position. 105

16. In a margin-stop mechanism for type-writing machines, the combination of a carriage, coöperating stops for normally arresting the carriage at a predetermined point in its travel, means for locking one of said stops in its normal position, a cam for releasing said locking means, and hand-actuated means for throwing said cam into operative position, so that the locking means will be automatically released during the travel of the carriage when said cam is in the operative position. 110

17. In a margin-stop mechanism for type-writing machines, the combination of a carriage, coöperating stops for normally arresting the carriage at a predetermined point in its travel, means for locking one of said stops in its normal position, a cam for releasing said locking means and affording a movement of the stop controlled thereby, hand-actuated means for throwing said cam into operative position, so that the locking means will be 120

automatically released and the stop controlled thereby will be moved from its normal position during the travel of the carriage and when said cam is in the operative position, 5 means for automatically restoring the released stop to its normal position, and means for automatically locking it in such position.

18. In a margin-stop mechanism for type-writing machines, the combination of a carriage, a stop-rod, a stop carried by and adapted to be shifted along said rod, a second stop coöperating with the first-mentioned stop to arrest the carriage at a predetermined point in the travel thereof, means for locking the 15 shiftable stop in its normal position, a finger-piece, means controlled by said finger-piece and coöperating with said locking means during the travel of the carriage for releasing the locking means and affording a shifting movement of said shiftable stop, so that the carriage may move beyond the point where it is normally arrested by said stops.

19. In a margin-stop mechanism for type-writing machines, the combination of a carriage, a stop-rod, a stop carried by and adapted to be shifted along said rod, a second stop coöperating with the first-mentioned stop to arrest the carriage at a predetermined point in the travel thereof, means for locking the 25 shiftable stop in its normal position, a finger-piece, means controlled by said finger-piece and coöperating with said locking means during the travel of the carriage, for releasing the locking means and affording a shifting movement of said shiftable stop, so that the carriage may move beyond the point where it is normally arrested by said stops, and means for automatically restoring the shiftable stop to its normal position and for automatically locking it in such position.

20. In a margin-stop mechanism for type-writing machines, the combination of a carriage, a stop-rod carried by the frame of the machine, a spring-restored stop carried by 45 and adapted to be shifted along said rod, a second stop carried by the carriage and coöperating with the first-mentioned stop to arrest the carriage at a predetermined point in the travel thereof, means for locking the shift-50 able stop in its normal position, a finger-piece carried by the carriage, and means controlled by said finger-piece and coöperating with said locking means during the travel of the carriage, for releasing the locking means and 55 affording a shifting movement of said shiftable stop, so that the carriage may move beyond the point where it is normally arrested by said stops.

21. In a margin-stop mechanism for type-writing machines, the combination of a carriage, a stop-rod, a spring-restored stop carried by and adapted to be shifted along said rod against the pressure of its spring, means for adjusting said stop in the direction of the 60 travel of the carriage, a second stop coöperat-

ing with the first-mentioned stop to arrest the carriage at a predetermined point in the travel thereof, means for locking the shiftable stop in its normal position, a finger-piece, means controlled by said finger-piece and co- 70 operating with said locking means during the travel of the carriage for releasing the locking means and affording a shifting movement of said shiftable stop, so that the carriage may move beyond the point where it is normally arrested by said stops, and will be automatically restored to its normal position when the carriage is returned from the point beyond where it is normally arrested, and means for automatically locking the shiftable 80 stop in its normal position.

22. In a margin-stop mechanism for type-writing machines, the combination of a carriage, a stop adapted to be shifted for a limited distance from its normal position and in 85 the general direction of the travel of the carriage, means for automatically locking said stop when it is in its normal position, a second stop coöperating with the first-mentioned stop to arrest the carriage at a predetermined 90 position, a cam for releasing the locking means to afford a shifting movement of the shiftable stop, so as to enable the carriage to move beyond the predetermined point where it is normally arrested, a finger-piece on the 95 carriage for controlling said cam, and means for automatically restoring the shiftable stop to its normal position.

23. In a margin-stop mechanism for type-writing machines, the combination of a carriage, a shiftable stop adapted to receive a shifting movement in the general direction of the travel of the carriage, a spring-pressed locking device for locking said stop to its support, means that are adapted to be brought 100 into contact with said spring-pressed locking device during the travel of the carriage to move it against the pressure of its spring, and a second coöperating stop.

24. In a margin-stop mechanism for type-writing machines, the combination of a carriage, a spring-restored shiftable stop adapted to receive a shifting movement in the general direction of the travel of the carriage and against the pressure of its spring, a spring-pressed locking device for automatically locking said stop to its support when the stop is in the normal position, means that are adapted to be brought into contact with said spring-pressed locking device during the travel of 115 the carriage to move it against the pressure of its spring to afford a shift of the stop, and a second coöperating stop.

25. In a margin-stop mechanism for type-writing machines, the combination of a carriage, a shiftable stop adapted to receive a shifting movement in the general direction of the travel of the carriage, a spring-pressed locking device for locking said stop to its support, means that are adapted to be brought 120

into contact with said spring-pressed locking device during the travel of the carriage to move it against the pressure of its spring to afford a shift of the stop, means for maintaining the locking device out of engagement when it is released and the stop is shifted and for automatically affording a reengagement of the locking device when the stop reaches the normal position, and a second coöperating stop.

26. In a margin-stop mechanism for type-writing machines, the combination of a carriage, a spring-restored shiftable stop adapted to receive a shifting movement in the general direction of the travel of the carriage, a spring-pressed locking device for locking said stop to its support, means that are adapted to be brought into contact with said spring-pressed locking device during the travel of the carriage to move it against the pressure of its spring and to afford a shift of the stop, a cam for maintaining the locking device out of engagement when it is released and the stop is shifted and for automatically affording a reengagement of the locking device when the stop reaches the normal position, and a second coöperating stop.

27. In a margin-stop mechanism for type-writing machines, the combination of a carriage, a final stop, an initial stop adapted to move for a limited distance relatively to said final stop, means for locking the initial stop

relatively to the final stop, means which are adapted to be rendered effective through a movement of the carriage for releasing the locking means to afford a movement of the initial stop until it is arrested by the final stop, and a stop which coöperates with said initial stop.

28. In a margin-stop mechanism for type-writing machines, the combination of a carriage, a final stop, an initial stop adapted to move for a limited distance relatively to said final stop, means for locking the initial stop relatively to the final stop, means which are adapted to be rendered effective through a movement of the carriage for releasing the locking means to afford a movement of the initial stop until it is arrested by the final stop, a stop which coöperates with said initial stop, means for automatically restoring the initial stop to its normal position, and means for automatically affording an operation of said locking means to lock the initial stop when it is in the normal position.

Signed at the borough of Manhattan, city of New York, in the county of New York and State of New York, this 8th day of October, A. D. 1903.
